UNITED STATES PATENT OFFICE.

ADOLPH H. HENDRICKSON, OF ORLAND, CALIFORNIA.

FOLDING TOOTH-BRUSH.

1,304,769.

Specification of Letters Patent. Patented May 27, 1919.

Application filed September 8, 1917. Serial No. 190,332.

To all whom it may concern:

Be it known that I, ADOLPH H. HENDRICKSON, a citizen of the United States, residing at Orland, in the county of Glenn, State of California, have invented a new and useful 5 Folding Tooth-Brush; and I do hereby declare the following to be a full, clear, and exact description of the invention, such as will enable others skilled in the art to which 10 it appertains to make and use the same.

The present invention relates to certain new and useful improvements in tooth brushes, and has for its object to provide a device of this character which is collapsible and embodies novel features of construction whereby it can be compactly folded and carried in the pocket or packed in a small amount of space.

Other objects of the invention are to provide 20 a folding tooth brush which is comparatively simple and inexpensive in its construction, which can be quickly folded or extended for use, and which provides a dust-proof and antiseptic compartment for the 25 bristles of the brush.

With these and other objects in view, the invention consists in certain novel combinations and arrangements of the parts as will 30 more fully appear as the description proceeds, the novel features thereof being pointed out in the appended claims.

For a full understanding of the invention, reference is to be had to the following 35 description and accompanying drawing, in which:

Fig. 1 is a side elevation of a collapsible tooth brush constructed in accordance with the invention, showing the same as folded.

Fig. 2 is a similar view with one of the 40 side pieces of the handle removed to show the interior construction of the handle.

Fig. 3 is a side elevation of the brush when opened up for use, a partly closed position being indicated by dotted lines, and portions being broken away and shown in section.

Fig. 4 is a top plan view of the brush when opened up for use.

Fig. 5 is a transverse sectional view 50 through the handle, on the line 5—5 of Fig. 4.

Fig. 6 is a detail perspective view of one of the antiseptic receiving side strips.

Corresponding and like parts are referred 55 to in the following description and indicated

in all of the views of the drawing by like reference characters.

Referring to the drawings, which illustrate one embodiment of the invention, the reference character A designates the handle, 60 and B the brush element which is pivotally connected to the handle and adapted either to be collapsed against the handle or swung outwardly into alignment therewith. The handle A has a hollow formation and includes opposed and spaced side plates 1 and a back 2 which is interposed between the lower edges of the side plates, one end of the back terminating in a spring arm 2^a, while the opposite end thereof is provided 70 with an end plate 3. Suitable fastening members such as the rivets 4 are provided for securing the parts of the handle together. The interior of the handle is subdivided by an intermediate transverse partition 5 into a brush receiving compartment C and a tooth paste receiving compartment D.

The brush member B is formed with a head 6 which carries the bristles 7, and also 80 with a shank 8 which extends longitudinally from one end of the head 6 and terminates in a pivot plate 9 which is received between the free ends of the side plates 1 of the handle and mounted upon the pin 10. Flat 85 sides 9^a are provided upon opposite sides of the pivot plate 9 and arranged for engagement with the spring arm 2^a of the back, to hold the brush in either an open or a closed position. The opening of the brush is 90 limited by engagement of a shoulder 11 at the end of the shank 8 with the end of the spring arm 2^a.

A finger piece 12 is applied to the brush member B and provides a convenient means 95 for obtaining a hold on the same with the fingers when opening the brush. When the brush is closed the bristles 7 are received in the compartment C of the handle, the projecting edges of the back 6 engaging the side plates 1, and end piece 3, thereby providing a dust-proof closure. In order to maintain the brush in a sanitary condition and prevent it from becoming sour or infected, antiseptic carrying strips 14 are arranged with 100 in the compartment C, said strips extending along opposite sides of the compartment so as to be arranged at the sides of the bristles of the brush. The ends of the strips 14 terminate in ribs 14^a which are loosely received 110

within grooved portions 15 of the partition 5 and end piece 3, thereby enabling the strips to be readily slipped into and out of position, but holding them securely against 5 displacement when the brush is closed. These strips 14 have a hollow formation, being filled with antiseptic material 16, and being perforated on their inner sides, as indicated at 17.

10 The tooth paste is preferably packed in a small tube or container 17 which is of a suitable size to fit within the compartment D of the handle. Spring arms 18 are arranged upon opposite sides of this compartment D and constructed to have a resilient engagement with the paste containing tube 17 for the purpose of holding the same securely in position and preventing rattling thereof when the brush is packed. A wing 19 projects from the pivot plate 9 of the brush member in a spaced and parallel relation to the shank 8, being arranged to extend under the neck 17^a of the tube 17 when the latter is in position within the handle 20 and the brush is collapsed, as indicated by Fig. 2. Upon opening the brush, however, this wing 19 will engage the neck of the tube 17 and swing the same upwardly into such a position that it can be readily grasped 25 by the fingers and manually withdrawn from the handle. This is indicated by the dotted line position of the brush member on Fig. 3. Provision is thus made for carrying a supply of tooth paste, and also for 30 keeping the brush fresh and sanitary at all times.

I claim:

1. A folding tooth brush including a hollow handle formed with a brush receiving 40 compartment, antiseptic receiving strips fitted removably at the sides of the brush receiving compartment, a brush, a shank carrying the brush and pivotally connected to the handle so that the brush can be folded against the handle and received within 45 the compartment when not in use.
2. A folding tooth brush including a hollow handle formed with a brush receiving compartment, antiseptic receiving strips re- 50 movably arranged at the sides of the compartment and adapted to be withdrawn through the mouth of the compartment, and a brush element formed with a bristle carrying head and a shank, the shank being piv- 55 oted upon the handle so that the brush can be folded against the handle and the bristles housed within the compartment when not in use, the head then closing the mouth of the

compartment and retaining the antiseptic receiving strips in position.

3. A folding tooth brush including a hollow handle formed with a brush receiving compartment having corresponding grooves in the opposite ends thereof, antiseptic receiving strips arranged at the sides of the 65 compartment and formed at their ends with ribs which are loosely received within the grooves, the strips being removable through the open side of the compartment, and a brush element formed with a bristle carrying head and a shank, the shank being pivoted upon the handle so that the bristles can be swung into the brush receiving compartment when not in use, the head then closing the compartment and serving to hold the 75 antiseptic receiving strips in position.

4. A folding tooth brush including a hollow handle formed with a brush receiving compartment and a paste tube receiving compartment, a brush formed with a shank 80 terminating in a plate which is pivoted within the handle at one end of the paste tube receiving compartment, the brush being adapted to be folded into the brush receiving compartment, and a wing projecting 85 from the pivot plate of the shank in a substantially spaced and parallel relation to the shank, said wing being adapted to engage the end of a paste receiving tube to lift the tube out of the compartment when 90 the brush is opened.

5. A folding tooth brush including a hollow handle formed with spaced side pieces, a partition sub-dividing the hollow handle into a brush receiving compartment and a 95 paste receiving compartment, a brush element including a bristle carrying head and a shank, the shank terminating in a plate which is pivoted between the spaced sides of the handle so that the brush element can 100 be folded against the handle with the bristles housed within the brush receiving compartment, and a wing projecting from the pivot plate of the brush element in a spaced and parallel relation to the shank, said wing 105 being adapted to engage the end of the paste receiving tube to lift the same out of its compartment when the brush is opened.

In testimony whereof I have signed my name to this specification in the presence of 110 two subscribing witnesses.

ADOLPH H. HENDRICKSON.
